UNITED STATES PATENT OFFICE.

JAMES C. MILLER, OF PITTSBURGH, AND ANDREW ISLES, OF SWISSVALE, PENNSYLVANIA, ASSIGNORS TO THE W. R. MILLER COMPANY, A CORPORATION OF PENNSYLVANIA.

GAS-PRODUCER.

1,373,443.

Specification of Letters Patent.

Patented Apr. 5, 1921.

Application filed June 14, 1919. Serial No. 304,323.

To all whom it may concern:

Be it known that we, JAMES C. MILLER and ANDREW ISLES, citizens of the United States, and residents of Pittsburgh and Swissvale, respectively, in the county of Allegheny and State of Pennsylvania, have made a new and useful Invention in Gas- Producers, of which the following is a specification.

10 This invention relates to gas producers and more particularly to that type of producer having a revolving body portion.

An object of this invention is to produce means in the above type of producer by 15 which blasts in addition to the central blast may be directed into the fuel bed at various points around its outer edge or border.

A still further object is to provide in a 20 producer of the above type having a revolving ash pan and rotating body portion, a stationary water-sealed wall or bustle pipe surrounding the producer between the body portion and ash pan through which wall a number of blasts may be directed so as to 25 reach the outer portion of the fuel bed thereby increasing the output and efficiency of the producer.

A still further object is to provide continuously operating means for automatically 30 removing the clinker which forms along the inner surface of the revolving body portion of the producer.

These, as well as other objects which 35 will readily appear to those skilled in the producer art, we attain by means of the device described in the specification and illustrated in the drawings accompanying the same and forming a part of this application and throughout which similar elements are 40 denoted by like characters.

In the drawings, Figure 1 is a sectional elevation of a gas producer embodying this invention, Fig. 2 is a top plan view of the producer shown in Fig. 1, Fig. 3 is a fragmentary detail view showing a portion of the mechanism for rotatably supporting the body portion of the producer, Fig. 4 is an enlarged detail view of the clinker grinder, Fig. 5 is a cross sectional view of the clinker grinder and Fig. 6 is an enlarged view of a portion of the operating mechanism.

The producer proper consists of a cylindrical shell or body portion built up in any suitable manner and as shown in the draw-

ings consists of an outer steel shell 6; and a 55 brick lining 7 supported on an angle 8. The body portion is provided with a water-seal trough 9 at its top into which a depending annular flange 10 formed on top plate 11 projects. The top plate or cap 11, which is 60 stationary, is supported from the operating floor 12 of the producer house by means of suitable supporting feet 13 formed in any suitable manner.

Body 6 is provided with a support ring 65 14 adjacent its center and this ring is adapted to rest on suitable support rollers 15 carried in suitable standards 16 preferably arranged around the producer at 90° one from the other as shown in Fig. 2. These support 70 brackets also carry guide rollers 17 which bear against the steel jacket 6 of the body portion. Ring 14 is provided with gear teeth 18 in its outer periphery and these teeth mesh with a pinion or gear 19 carried 75 on a vertical drive shaft 20.

A grate made up of grids 21 secured together in the form of an inverted frustum of a cone is secured to the outer side of angle 8 and forms a bosh through the perforations of which suitable blasts of air and steam are directed to the fuel bed located 80 within the producer.

An ash pan 22 built-up in any suitable manner is rotatably supported on a central 85 standard 23 by means of two annular series of balls 24 and 25 which rest upon suitable races formed therefor on the central stand ard.

A central twyer 26 carried by the ash pan 90 is arranged to be supplied with a suitable blast of steam and air by means of a pipe 26a and is ported so as to discharge the blast at the center of the fuel bed. An annular depending apron 27 secured to the underside 95 of the grate projects into the ash pan a sufficient distance below the normal water level therein to provide a water-seal.

An annular flange 28 is also carried by the grate and projects into a water trough 29 carried by a stationary bustle pipe 30. Bustle pipe 30 at its top carries a water trough 31 within which an annular flange 32 carried by angle 8 projects. Flanges 28 and 32 co-operating with water troughs 29 100 and 31 seal the joints above and below the revolving grate, and stationary blasts 33 (three being preferably used) have their 105

discharging nozzles 34 projecting through openings formed therefor in stationary bustle pipe 30.

The under portion of the ash pan 22 at 5 its center is provided with a miter gear element 35 which meshes with a miter gear 36 carried on a horizontal shaft 37, which shaft is driven by miter gear 38 from vertical drive shaft 20. These gears are so proportioned that the body 6 and the ash pan 22 10 rotate at the same speed and in the same direction. A stationary ash scoop or scraper 39 which may be adjusted by means of a hand wheel 40 projects into the ash pan 22 15 and automatically removes ash therefrom as is now common.

Top plate 11 of the producer is provided with a fuel opening 41 above which any suitable fuel feeding device may be located. 20 The top plate is also provided with manholes 42 and an oscillating stirring arm or poker 43 as is now common. The top plate 11 adjacent one of the manholes 42 is provided with an opening 44 surrounded by an 25 upwardly extending annular flange 45 and a downwardly extending annular flange 46 and the combined inner bores of these two flanges is preferably tapered as shown in Fig. 4. Through this tapered bore a clinker 30 grinder 47 extends. The clinker grinder consists of a lower grinding portion 48 which lies in close proximity to the inner 35 surface of the revolving body of the producer and is preferably fluted on its outer surface as shown in Fig. 5 and hexagonal internally. The upper extremity of the lower portion at 49 is preferably cylindrical and fits with a drive or shrink fit into the lower portion of the upper part of the 40 clinker grinder, which upper part is preferably externally tapered as shown in Fig. 4 to correspond to the inner taper of the flanges 45 and 46.

A flange 50 spaced from flange 45 surrounds the same and with flange 45 forms a water trough. Bolted or otherwise secured to the upper part of the clinker grinder is a plate 51 from which an annular flange 52 depends, and, extending into the water trough formed by flanges 45 and 50 cooperates therewith to form a seal for the clinker grinder. Plate 51 on its under side is provided with a race for an annular series of balls 53 which are supported in a race 55 formed in the upper edge of flange 50. Plate 51 also carries a gear 54 which meshes with a gear 55 carried on a horizontal shaft 56 and which, by means of gears 57, 58, 59 and 60 is driven from the operating motor 61 conveniently located on the operating floor 12. The gears just described are so proportioned and arranged as to rotate the clinker grinder in the same direction as the direction of rotation of the body of the producer but at such a speed as will effectively

grind or crush and remove the clinkers from the inner side of the brick lining 7 as the rotating body moves past the clinker grinder. Cooling water is supplied to the interior of the clinker grinder through a depending pipe 62 and rising up around this pipe overflows through a port 63 into the water-seal surrounding the top of the clinker grinder. Vertical shaft 20 is driven from motor 61 by means of gears 60, 59 and gear 58 secured to the top of said shaft 20.

The coal feeding mechanism may be automatically operated through the agency of a reciprocating rod 70 operated from the motor through suitable mechanism as is now common and the poker 43 may be operated from the same motor.

Each of the grids forming the grate is provided with air openings 71 and at its center each grid is provided with a blank 85 space 72 which acts as a deflector for the blasts directed from nozzles 34 and causes them to be broken up and to issue through the openings 71 into and through the fuel bed lying thereagainst.

It has been found that the capacity of the producer, as well as its efficiency, is increased by directing the major portion of the air and steam supply into the fuel bed through the stationary blast devices 33 arranged 95 around the producer. The blast directed through central twyer 26 serves as a supplemental blast, and, if desired the central blast may be independently controlled from the outer blasts. All of the water for the water-seal troughs may, if desired, be supplied through pipe 62, (the pipe leading into the clinker grinder) and from the trough surrounding the clinker grinder may overflow into the trough sealing the joint between the 100 top plate and the revolving body and from this flow in series into the two troughs above and below the stationary bustle pipe and from there to the ash pan.

In accordance with the provisions of the 110 patent statutes we have described the principle of the operation of our invention, together with the device which we now consider to represent the best embodiment thereof, but we desire to have it understood 115 that the device shown is only illustrative and that the invention can be carried out in other ways.

Having thus described our invention what we claim as new and desire to secure by Letters Patent is—

1. In a gas producer, a revolving body portion, a revolving ash pan, a stationary blast device located outside of the producer, a stationary bustle pipe located between the 125 body portion and the ash pan and through which the blast device discharges, and means for sealing the joints between the revolving portions of the producer and the stationary portions.

2. In a gas producer, a revolving body portion, a revolving ash pan, a stationary blast device located outside of the producer, a stationary bustle pipe located between the body portion and the ash pan and through which the blast device discharges, and water-seals between the revolving portions of the producer and the stationary portions.
3. In a gas producer, a revolving body portion, a revolving ash pan, stationary blast devices arranged around the producer, a grate carried by the body portion through which said blasts are directed, a stationary bustle pipe surrounding the producer adjacent said grate and through which said blast devices discharge, and means for sealing the joints between the bustle pipe and the revolving portions of the producer.
4. In a gas producer, a revolving body portion, a revolving ash pan, stationary blast devices arranged around the producer, a grate carried by the body portion through which said blasts are directed, a stationary bustle pipe surrounding the producer adjacent said grate and through which said blast devices discharge, and water-seals for the joints between the bustle pipe and the revolving portions of the producer.
5. In a gas producer having a revolving body portion carrying a grate and a revolving ash pan below said grate, a stationary bustle pipe surrounding the producer adjacent the grate, blast devices discharging through said bustle pipe, a central blast device projecting through said ash pan and rotatable therewith and water seals for sealing the joints between said bustle pipe and the revolving body portion.
6. In a gas producer, a cylindrical body portion, means for rotatably mounting said body portion, an inwardly inclined grate carried by said body portion, an ash pan below said grate, means for rotatably supporting said ash pan, a stationary bustle pipe surrounding said grate, water seal troughs for sealing the joints between said bustle pipe and the revolving body portion, blast devices extending through said bustle pipe, and means for revolving said body and said ash pan in the same direction and at the same speed.

In testimony whereof, we have hereunto subscribed our names this 7th day of June, 1919.

J. C. MILLER.
ANDREW ISLES.
